HANDY IRON

Gertrude T. Gross, New York, N. Y.

Application December 21, 1948, Serial No. 66,407

6 Claims. (Cl. 38—69)

1

The present invention relates to what I term a handy ironer capable of applying to various articles either dry or vapor heat, as required.

The object of my invention is to provide a portable hand applicable ironing device adapted for use in various fields of endeavor, for example: in the millinery art for pressing or steaming hats, ribbons, velvets, chiffons and the like; in the dressmaking art for steaming garments on bust forms, hangers or the like; in the men's apparel art for steaming neckties on a rack or pressing garments; around the home for refreshing and removing wrinkles from slip covers, draperies and the like; and for personal use in steaming oil into the hair, steaming a cold and for applying warm, moist applications to the face of other parts of the body.

The foregoing and other objects of my invention not specifically described I accomplish through the novel handy ironer which is herein-after described and illustrated in the drawings, wherein:

Figure 1 shows an axial section through a device embodying my invention.

Fig. 2 shows a section taken along the plane of the line 2—2 of Fig. 1.

Fig. 3 shows a section on a greatly enlarged scale taken along the line 3—3 of Fig. 1.

The handy iron of my present invention may be said to consist of a hollow casing 10, a liquid reservoir 11, an electrical heating element 12, vapor pressure chambers 13 and 14, and a handle 15, the said parts being coordinated and assembled to provide a portable device.

The casing 10 may be formed of any suitable material, preferably metal having an outer polished surface and, as herein shown, consists of two sections 10a and 10b, the section 10a being of generally conical form and the section 10b being of substantially semi-spherical form and being connected to the section 10a by a lap joint 16 and suitable securing means 17. The section 10a at its apex end is preferably of semi-spherical form and is formed with a plurality of spaced openings 18 through which vapor under pressure, for example, steam, may escape from the vapor pressure chambers.

The liquid reservoir 11, which may be of any desired configuration, is disposed within the casing and is herein shown as being of substantially truncated conical form having a flat top 19 and a flat base 20, the latter being provided with a packing disc 21 carried in a closure cap member 22. The liquid reservoir has a plurality of openings or ports 23 formed in its wall, eight such

2

ports being herein shown and each of said ports is controlled by a flapper or cantilever spring valve 24 which is normally open but of a character such as will close under the pressure of water within the reservoir acting thereagainst. The ports 23 and valves 24 are so disposed within the reservoir that, regardless of the position in which the device is held, some of said ports will remain open to provide for the escape of vapor generated within the liquid reservoir into the vapor chamber 13.

The vapor pressure chamber 13 is constituted by the liquid reservoir 11 and a casing 25 surrounding and spaced from said reservoir. The chamber 13 may be held in fixed relation to the reservoir 11 in any preferred manner and, as herein shown, the reservoir 11 is formed with spaced longitudinally extending ribs 26 which at their outer ends may be secured to the casing 25 by spot welding, soldering or equivalent means. At its inner end the vapor pressure chamber 13 is sealed by the packing 21 within the closure cap 22 which simultaneously seals the liquid reservoir 11. At its outer end the vapor pressure chamber 13 connects with the vapor pressure chamber 14 through a coil 27. The vapor pressure chamber 14 is held within the casing 10 by screws 28 engaging within the openings 18, said screws 28 each having an axial passage 29 extending therethrough and the heads of the screws being flush or seating below the surface of the casing 10.

Disposed within the casing so as to surround the vapor pressure chamber 13 and the coil 27 is the electrical heating unit 12 which may be of any approved or desired construction and said unit is preferably in contact with the outer wall of the casing 25 so as to supply heat directly to the liquid reservoir by conduction through the contacting surfaces of said reservoir and casing 25. If desired, additional electrical heating means 12a may be disposed at the base of the liquid reservoir to supply additional heat thereto. The electrical heating elements 12 and 12a have leads extending through the casing to contact pins 30 designed to accommodate a conventional electrical plug.

For supplying liquid to the reservoir 11 there is provided a filler tube 31 which extends through the handle 15 into the reservoir 11 and is connected to said parts in any desired manner, for example, to the reservoir by means of a screw-threaded connection between the inner end of the tube 31 and a nipple 22a on the closure cap 22 and to the handle by a set screw 15a and a closure

plug 32. Preferably a spacer disc 33 is disposed around the filler tube between the electrical heating element 12a and the casing section 10b and a heat guard 34 is disposed between the casing section 10b and the inner end of the handle 15. A suitable packing 35 is disposed between the end of the handle 15 and the closure plug 32 to insure against leakage of liquid from the reservoir.

In order to prevent the building up of excessive pressure within the liquid reservoir, in the event that any of the valves 24 may stick in closed position, a relief valve 36 of any preferred construction may be mounted therein and extend through the casing section 10b.

In the use of the device the closure plug 32 is removed and a desired quantity of liquid, less than required to fill the reservoir, such as water, or water containing additives where the device is to be used for steaming oil into the hair or generating a medicated vapor, is introduced into the liquid reservoir and the closure plug replaced. Of course any type of check valve (not shown) may be mounted within the filler tube 31 near the inner end thereof to prevent the liquid from the reservoir moving backwardly into the filler plug and for preventing generated vapor entering the filler tube and unduly heating the same. Upon connecting electric current to the contact pins 30, electrical energy is supplied to the heating elements and, in turn, heats the liquid within the reservoir, generates vapor which passes through the open ports controlled by the valves 24 into the vapor pressure chamber 13, from there through the coil 27 to the vapor pressure chamber 14, and then out through the axial passages 29 in the screws 28. During and prior to this vaporizing action of the liquid in the reservoir the casing 10 will be heated and thus serve as a pressing or smoothing iron for the purposes intended, which pressing operation, when supplemented by the escaping vapors through the openings 29, will operate to carry out the functions of the handy iron.

From the foregoing detailed description it will be appreciated that I have provided a relatively simple and compact device capable of performing all the objects set forth in the opening statement of this specification, and while I have shown and described a preferred embodiment of my handy iron, it is to be understood that changes in construction and arrangement of parts thereof may be resorted to within the range of engineering and mechanical skill without departing from the spirit of the invention as defined in the appended claims.

What I claim is:

1. An ironer comprising a hollow elongate casing having a curved outer ironing surface, a liquid reservoir within the casing and spaced therefrom, electrical heating means in the space between the liquid reservoir and the casing, a vapor pressure chamber within one end of the casing, valve means adapted to admit vapor generated within the liquid reservoir into the vapor pressure chamber, the casing having ports leading from the vapor pressure chamber to the outer surface of the casing, and a hollow handle at the

end of the casing remote from the end in which the vapor pressure chamber is located, said hollow handle leading to the liquid reservoir and providing means through which liquid may be introduced into the liquid reservoir.

5 2. An ironer according to claim 1 wherein the vapor pressure chamber is an element separate from the casing, and said vapor pressure chamber and the casing have communicating ports in contiguous parts thereof, the ports in the casing leading to the atmosphere.

10 3. An ironer according to claim 1 wherein the casing has an outer curved surface of generation and the handle is disposed coaxial with the casing.

15 4. An ironer according to claim 3 wherein the casing is of generally conical form and the handle is disposed at the base end of the casing and coaxial therewith.

20 5. An ironer comprising a hollow casing having an outer curved surface of generation, a liquid reservoir within the casing and substantially concentric therewith, said liquid reservoir having spaced apart walls, electrical heating means 25 between the liquid reservoir and the casing, vapor pressure confining means within the casing, said confining means comprising a chamber within one end of the casing, a second chamber provided by the spaced apart walls of the liquid 30 reservoir and a helical coil connecting the two chambers, and valve means controlling ports in the liquid reservoir leading to the chamber provided by the spaced apart walls of the liquid reservoir for admitting vapor generated in the reservoir into said last mentioned chamber.

35 6. An ironer comprising a hollow casing having an outer curved surface of generation terminating at one end in a substantially hemispherical portion, a liquid reservoir within the 40 casing coaxial with and spaced therefrom, electrical heating means in the space between the liquid reservoir and the casing, a vapor pressure chamber within the hemispherical end portion of the casing, valve means for admitting vapor generated within the liquid reservoir into the vapor pressure chamber, and the casting having ports leading from the vapor pressure chamber to the outer surface of the hemispherical portion.
